[57] CLAIM

The ornamental design for a waste receptacle, as shown and described.

DESCRIPTION

FIG. 1 is a front perspective view of a waste receptacle showing my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof;

FIG. 8 is a fragmentary sectional view thereof, taken along line 8—8 of FIG. 2;

FIG. 9 is a front perspective view of a second embodiment of the waste receptacle;

FIG. 10 is a top plan view of FIG. 9;

FIG. 11 is a fragmentary sectional view taken along line 11—11 of FIG. 10;

FIG. 12 is a front perspective view of a third embodiment of the waste receptacle;

FIG. 13 is a top plan view of FIG. 12;

FIG. 14 is a front elevational view of FIG. 12, the rear elevational view being a mirror image of that shown;

FIG. 15 is a side elevational view of FIG. 12, the opposite side elevational view being a mirror image of that shown;

FIG. 16 is a fragmentary sectional view taken along line 16—16 of FIG. 13.

The undisclosed rear, bottom and sides of FIG. 9 and bottom of FIG. 12 are the same as the FIGS. 4, 5, 6 and 7.
